SUPPORT FOR A DRUM STAND

Josephus B. Thompson, deceased, late of Covington, Ohio, by K. E. Stade, administrator, Covington, Ohio, assignor to Columbia Broadcasting System, Inc., New York,
N.Y., a corporation of New York

Filed Oct. 9, 1968, Ser. No. 13,916

Term of patent 14 years

Int. Cl. D17—04

U.S. Cl. D56—1

FIG. 3.

FIG. 4.

FIG. 5.

FIG. 6.

What is claimed is:

The ornamental design for a support for a drum stand, substantially as shown and described.
